APRON

Amanda E. Liddell, 901 Jefferson Ave., Brooklyn 21, N.Y.

Filed May 8, 1963, Ser. No. 74,803

Term of patent 7 years

(Cl. D3—26)

FIG. 1

FIG. 2

FIG. 3

FIG. 1 is a perspective view of an apron showing my new design;

FIG. 2 is a rear elevational view thereof; and

FIG. 3 is a front elevational view.

My apron design comprises two embroidered, scalloped tiers stitched together substantially along the upper edge of the lower tier, in combination with a matching scalloped waistband, the scalloping extending through the ties, together with two symmetrically arranged rose-like ornaments, at each end of the waistband, and a larger, matching rose-like ornament on the upper tier, all as shown.

I claim:

The ornamental design for an apron, as shown and described.
